(57) **CLAIM**

The ornamental design for a five-piece fuselage, including engines and wings, for a aerodynamically stable, high-lift, vertical takeoff aircraft, as shown and described.

DESCRIPTION

FIG. 1 is a top/side perspective view of a five-piece fuselage, including engines and wings, for a aerodynamically stable high-lift, vertical take-off aircraft of my new design; FIG. 2 is a side elevational view thereof, the other side elevational views being identical to FIG. 2; FIG. 3 is a top plan view thereof; and, FIG. 4 is a bottom plan view thereof.
